UNITED STATES PATENT OFFICE.

ALBERT L. WOLFSON, OF NEW YORK, N. Y.

TURBO-BLOWER.

No. 910,086.

Specification of Letters Patent. Patented Jan. 19, 1909.

Application filed February 21, 1908. Serial No. 417,064.

To all whom it may concern:

Be it known that I, ALBERT L. WOLFSON, a citizen of the United States, residing at New York, in the borough of Manhattan, county and State of New York, have invented certain new and useful Improvements in Turbo-Blowers, of which the following is a specification.

This invention relates to an improved 10 turbo-blower in which a steam-turbine is connected with a blower or ventilating fan.

The object of this invention is to furnish 15 a blower or ventilator driven by a steam-turbine for moving air, gases, and other fluids, either to or from a particular locality and permit the air or other fluid that is set 20 in motion to be heated by the exhaust-steam to a higher temperature so as to be used as a forced draft for the furnaces of steam-boilers and other applications; and for this 25 purpose the invention consists of a blower or ventilator the rotatable blades of which are applied to a hub which forms the shell or casing for a steam-turbine the vanes of 30 which are arranged in said hub and rotated by steam admitted through one or more stationary nozzles and exhausted through ports at the inner end of the hub.

The invention consists further of a coil 35 located in the casing of the blower and connected with the exhaust-end of the steam-turbine in the hub by means of a hood so as to permit the heating of the air or other fluid forced by the blower through the casing when the heating of the air to a higher 45 temperature is required.

In the accompanying drawings, Figure 1 represents a vertical longitudinal section of 50 my improved turbo-blower, Fig. 2 is a vertical transverse section on line 2, 2, Fig. 1, and Fig. 3 is a diagrammatic section of the steam-turbine in the hub of the blower showing the method of supply and exhaust of the steam to and from the vanes of the turbine.

Similar letters of reference indicate corresponding parts.

Referring to the drawings, *a* represents the casing of my improved blower or ventilator, *a*¹ an adjustable ring at the ingoing 55 end of the casing, and *b* a number of fan blades that are set at a suitable angle to the longitudinal axis of the casing and secured to the outer wall of a hollow hub *d* which is rotated on a hollow stationary shaft *e* that is supported in a center-bearing *f* of a spider-frame *f*¹ attached to the ring *a*¹ at

the ingoing end of the casing. In the hollow hub *a* are arranged the vanes *i* of a steam-turbine, to which steam is supplied by one or more stationary nozzles *n* which are connected with an annular steam-chamber *n*¹, that is attached by screw-bolts *n*² to the center-bearing *f*. The nozzle or nozzles *n* are fitted into sockets at the ingoing end of the hub, the steam passing through the vanes 60 axially of the turbine to the inner or outgoing end of the hub and through exhaust-ports *n*³ into the casing *a* to be carried along by the air or other fluid set in motion by the blades of the blower, or to be conducted by a 65 hood *h* which is screwed onto the outer circumference of the inner end of the hub *d* and a suitable discharge-pipe to a condenser. The tubular shaft *e* is closed at its outer and inner ends by screw-plugs *e*¹ *e*², and supplied 70 with lubricating oil from an oil-cup *e*⁴ on the bearing *f*, the oil being conducted through openings *o* in the bearing *f* to an interior bushing *d*¹ of the hub *d*, as shown in Fig. 1. The bushing *d*¹ has a shoulder *d*² at 75 its inner end which is fitted into an annular recess of the hub, while a cap *c* is screwed onto the inner circumference of the inner end of the hub and provided with a raised central steel-bearing *c*¹ which forms 80 contact with the raised center of the inner screw-plug *e*² so as to take up the thrust of the steam-turbine located in the hub of the blower or ventilator.

When the exhaust-steam from the steam-turbine is to be utilized for heating the air forced in by the blades of the blower, a coil *g* is supported by suitable keepers *g*¹ transversely in position in the casing *a*, said coil being composed of vertical pipes *g*² 95 which are connected at their upper and lower ends by arc-shaped pipes *g*³, as shown in Fig. 2. The central portion of the coil *g* is connected by horizontal pipes *g*⁴ with the vertical pipes *g*¹ and by a short-pipe *g*⁵ located at right angles to the plane of the coil *g* with a stuffing-box *g*⁶ on said pipe *g*⁵. On said stuffing-box rotates a hood *h*, the outer circumference of which is screwed to the outer circumference of the inner end of the hub *d*, so that as the hub rotates by the action of the steam-turbine in the same, the hood receives the exhaust-steam delivered through the exhaust ports *n*³ of the hub and conducts it through the connecting pipe *g*⁵, 100 the radial pipes *g*⁴, the vertical pipes *g*², and the arc-shaped pipes *g*³ of the heating coil *g* 105 110

to a discharge-pipe g^7 and to a condenser. The air is heated by contact with the heating coil to nearly the temperature of the exhaust-steam, the latter being drawn off by 5 the condenser from which the water of condensation is returned to the steam-boiler in the usual manner. The heated air or other fluid is conducted to the grate of the furnace of the steam-boiler for burning the fuel 10 under forced draft in an economical manner without requiring a chimney for producing the draft.

When the air or other fluid is not to be heated, then the heating coil and its connecting-pipe are removed from the casing, in 15 which case the exhaust-steam is carried by a discharge-pipe to the condenser, and the water of condensation returned to the boiler. The exhaust-steam may also be emitted from 20 the hood h into the casing a and carried along by the air or other fluid through the furnace-grate and the glowing fuel on the same, where the exhaust-steam is dissociated and thereby the more complete combustion 25 of the fuel obtained in connection with the oxygen of the air forced through the fuel.

The arrangement of the steam-turbine in the hub of the blower or ventilator permits 30 either the condensation of the exhaust-steam when drawn off to a condenser, or the carrying off of the exhaust-steam with the air to the furnace of the steam-boiler, or the heating up of the air or other fluid by the exhaust-steam and the return of the latter in 35 condensed form to the steam-boiler. By locating the steam-turbine in the hub of the blower, the power of the steam is utilized in the most effective manner for rotating the 40 blades, and the power-transmission from a driving-shaft dispensed with, so that the blower or ventilator can be placed at any desired position in proximity to the furnace which is to be operated under forced draft. 45 By reversing the angles of the blades to the hub, the fan can be used as an exhaust-ventilator or for induced draft in a boiler.

Having thus described my invention, I claim as new and desire to secure by Letters 50 Patent:

1. In a blower or ventilator, the combination, with a casing, of a stationary shaft, supported centrally in said casing, a hollow hub rotating on said shaft, a plurality of 55 blades located on said hub, vanes located in said hub, a steam-nozzle or nozzles for supplying steam to said vanes, at one end of the hub, and exhaust-ports at the other end of the hub.

60 2. In a blower or ventilator, the combination, with a casing, of a stationary journal-bearing supported centrally in said casing, a stationary shaft supported in said bearing, a hollow hub rotating on said shaft, blades

located on said hub, vanes located in said hub, a steam-nozzle or nozzles at the ingoing end of the hub, exhaust-ports at the outgoing end of the same, and a hood secured to the inner end of the hub for conducting off the exhaust-steam. 65

3. In a blower or ventilator, the combination, with a casing, of a stationary shaft supported centrally in said casing, a hollow hub rotating on said shaft, blades on said hub, vanes located in said hub, a steam-nozzle or nozzles at the ingoing end of the hub, exhaust-ports at the outgoing end of the same, and a cap attached to the inner end of the hub for taking up the thrust of the 70 same. 75

4. In a blower or ventilator, the combination of a rotatably mounted hub having interior turbine-vanes, a nozzle to supply steam to the hub at one end, a fixed outlet-pipe at the other end of the hub, and a hood 85 fixed to said hub and rotating around said outlet-pipe, said hood receiving the steam after its passage through the turbine-vanes. 80

5. In a blower or ventilator, the combination, with a casing, of a tubular shaft supported centrally in said casing and closed at the ends, a hollow hub rotating on said shaft, a plurality of blades located on said hub, means for supplying lubricating oil through the tubular shaft to the inner surface of the hub, a steam-nozzle or nozzles at the ingoing end of the hub, exhaust-ports at the outgoing end of the same, and a thrust-bearing for the hub at the inner end of the 90 same. 95

6. In a blower or ventilator, the combination, with a casing, of a shaft supported at the center of said casing, a hollow hub on said shaft, a plurality of blades on said hub, a steam-turbine in said hub for rotating the 105 hub and blades, a heating-coil extending transversely across the casing, and means connecting the exhaust-ports of the steam-turbine with said heating coil for heating the air or other fluid set in motion by the 110 blades. 100

7. In a blower or ventilator, the combination, with a casing, of a shaft supported at the center of said casing, a hollow hub on said shaft, radial blades extending from said 115 hub, a steam-turbine in the hollow hub, a hood extending over the exhaust-ports of the steam-turbine in the hub, a heating coil arranged transversely across said casing, and a connecting-pipe between the hood and coil 120 for conducting the exhaust-steam to the coil. 120

In testimony, that I claim the foregoing as my invention, I have signed my name in presence of two subscribing witnesses.

ALBERT L. WOLFSON.
